MEANS FOR FORMING AND DECODING
SECRET MESSAGES

Joseph B. Walker, Hollywood, Calif.

Application July 8, 1935, Serial No. 30,385

12 Claims. (Cl. 197—4)

This invention relates to apparatus for forming secret messages adapted for transmission to a distant station without the necessity for any synchronization between the apparatus of the 5 sending and receiving stations. The particular mechanism herein shown and described embodies not only means for forming a secret or code message by a sending station, but also for decoding messages received from another station.

Application Serial No. 704,040, Method of and means for recording and reproducing secret messages, filed December 26, 1933, constituting a renewal of my application 611,449, filed May 16, 1932 and of which applications the present application is a continuation in part, discloses some 15 of the broader principles of the present application.

It is a primary object of the invention to provide an apparatus of the character indicated, 20 adapted for the production and the subsequent deciphering of messages which it is impossible for any expert to "break".

Broadly stated, the invention contemplates the employment of characters indicative of letters of the alphabet, each character in turn being represented by a group of units. These latter may consist of dots and dashes, such as are employed in the Morse code.

In the preparation of the code message, I not 30 only scramble the complete characters indicative of the respective letters, but I scramble the fractional parts of such letters, in such manner that the integrity of the individual characters is completely lost by the reduction of the characters 35 to their component parts of dots and dashes and then heterogeneously scramble these units until the units present or constitute a sequence devoid of any characteristic significance and which significance can only be restored to its original 40 clear text form by means of this invention.

The letter having integrity as such has assigned to it a character composed of dots and dashes. The integrity of the letter is imparted to the character by the assigned sequence of dot 45 and dash. These units, the dots and dashes of a character, are then broken out of their characteristic sequence and altered by both substitution and transposition thereof into a garbled sequence, in which all integrity of the characters 50 has disappeared, and this is accomplished speedily and automatically.

Other objects and advantages of the invention will be set forth in the detailed description which follows.

In the accompanying drawings,

Figure 1 is a plan view of the machine constructed in accordance with the invention.

Fig. 2 is a fragmentary view illustrating a ribbon feed hereinafter described.

Fig. 3 is a perspective view of one of the type 5 bars and its associated solenoid magnet.

Fig. 4 is an end elevation of the mechanism with the base portion of its case illustrated in full lines and with the cover portion of the case illustrated in dotted lines.

Fig. 5 is a fragmentary sectional view illustrating one of the type bars, the platen and some of the magnets.

Fig. 6 is a transverse sectional view upon line 6—6 of Fig. 1, illustrating a type bar lifting 15 mechanism hereinafter described.

Fig. 7 is a view like Fig. 6 with the parts in another position, and Fig. 7a is a horizontal section on line 7a—7a of Fig. 7.

Fig. 8 is a perspective view of the platen and 20 some of the associated parts.

Fig. 9 is a fragmentary view illustrating a portion of the key board.

Fig. 10 is a horizontal sectional view through the stems of some of the keys and illustrating 25 the detent wires of said keys.

Fig. 11 is a detailed view of one of the keys upon an enlarged scale.

Fig. 12 is a diagrammatic view illustrating one 30 of the circuits employed.

Fig. 13 is a plan view of the case with the panels therein.

Fig. 14 is a fragmentary sectional view through the base upon line 14—14 of Fig. 13.

Fig. 15 is a detailed view illustrating the criss- 35 cross wiring of the center or transposition panel.

Fig. 16 is a detailed sectional view through one side of the key illustrating a swinging shield hereinafter described.

Fig. 17 is a diagrammatic view illustrating a 40 distributor which may be incorporated in the system if desired.

Like numerals designate corresponding parts in all of the figures of the drawings.

The particular form of apparatus which I have 45 shown for purposes of explanation comprises three general divisions, namely, a key board through which the operator closes certain electric circuits to form the respective characters; one or more changeable panels adapted to be inter- 50 posed in and to constitute parts of said electric circuits and serving, by the variations imposed by their presence upon said circuits, to bring about the substitution and transposition herein- after described, and a printing mechanism com- 55

prising a plurality of type bars controlled by said circuits, each of which bears a dot and dash, the position of the dot and dash with respect to the printing mechanism determining the nature of the garbled sequence of the units to be printed. The key board comprises a plurality of keys consisting of the heads 5 and shanks 6. These keys are mounted for vertical movement in plates 7 and 8. Springs 9 lie between the plate 8 and shoulders 10 of the shanks 6. When the buttons 5 are pressed against the tension of the springs 9 their ends momentarily engage contact points 11. When the buttons are released they are elevated by the springs 9 enough to bring the shank 6 out of contact with the contact point 11 but they do not return entirely to elevated position, but upon the contrary are held in a partly depressed position by wires 12 which engage an annular groove 13 of the shanks. It will be observed that the buttons are arranged in twelve rows of five buttons each and three rows of four buttons each. One side of a battery or other source of E. M. F. indicated at B is connected to any suitable part of the metallic frame of the machine indicated in a general way at 14. The other side of this battery is connected to the plate 8, the result being that when a key is depressed a circuit is completed from battery b to plate 8, shank 6 of the depressed key, a conductor 15, the substitution and transposition panels indicated at P, P¹ and P², conductor 16, and to a solenoid magnet 17, there being one of these magnets associated with each of the buttons 5. The metal shells of these magnets are grounded to the metallic plate 14 in which they are mounted and which constitutes a part of the framework of the machine. When the solenoids are energized their armatures 18 are drawn inwardly and out of engagement with the detent notches 19 of the printing or type bars 20. Springs 21 attached to the bars 20 tend to draw said bars downwardly. The bars are normally held in elevated position by the engagement of the detents (constituted by the armatures 18 of the solenoids) in the notches or recesses 19 of said bar. A platen 22 mounted upon a swinging frame 23 is adapted to be swung toward the printing elements constituted by the points 24 and short bars 25 of the printing bars 20 and to press a paper 26 or other message receiving surface against an ink ribbon 27 and to in turn press said ribbon against that one of the printing elements 24 or 25 which happens to be lying at the printing line X. The points 24, which constitute those elements which produce the dots upon the paper 26, normally lie at the printing line and if none of the buttons 5 were depressed only dots would be printed when the platen was forced against the ribbon. However, when a button is pressed and the corresponding type bar is released, its spring 21 draws said bar downwardly to such an extent as to move the "dash" printing element 25 on to the printing line.

As before stated, each character to be formed is made up of a plurality of units, these units being units controlled by the keys of a transverse row upon the key board. Thus, if only the third and fourth buttons in the first row are depressed the result will be to print the character consisting of two dots, two dashes and a dot if the sequence of the delivery of the electrical impulses is not interfered with by a garbling or scrambling process. In preparing a message, the operator starts at the top transverse row of buttons, depressed the desired buttons in each successive row until

the desired number of characters, within the capacity of the key board, have been formed, or in other words, until the corresponding type bars have been shifted to printing position. The frame 23 is then swung upon its pivot 23a to bring the paper 26 forcibly against the ribbon 27 in the manner hereinbefore set forth. This movement of the frame 23 is under the influence of an operating handle 29 and this handle serves the double function of moving the frame 23 and of resetting the parts for the printing of another line of units. However, before the platen is again pressed against the ribbon it is given a partial turn in a manner common in typewriters to space the paper ahead one step and to bring another portion of the paper into line with the printing characters upon the type bars.

The means for imparting this partial turning movement to the platen are like those commonly employed in typewriters and constitute no part of the present invention. It is thought a detailed description thereof is unnecessary.

The frame 23 is normally rocked away from the type bars under the thrust of springs 23b. The handle 29 has limited bodily movement upon a shaft 30. When thrust inwardly the arm 31 which projects from the hub 32 of said handle overlies a plunger 33 and when the handle 29 is moved outwardly or away from the type bars, the plunger is depressed and by its thrust upon the tail of an arm 34 rocks shaft 35 against the action of the spring 36. This elevates a reset bar 37 which extends from the outer end of arm 34 to the outer end of a corresponding arm 34a. The upward thrust of this reset bar 37 serves to reset the type bars because the bar 37 underlies the lower ends of these type bars and when the bar 37 is thrust upwardly such of the type bars as have been lowered are again lifted to such position that the detents 18 may snap into the notches 19. The rocking movement of the shaft 35 is also utilized to reset the buttons of the key board. This is accomplished through the medium of a crank 38 on shaft 35 which acts through a link 39 having an insulating element 40 in its length, to rock a shaft 41 through the medium of a crank arm 42. The rocking of the shaft 42 acts through a short crank arm 43 and link 44 to impart endwise movement to a frame comprising a plurality of longitudinally extending rigid bars 45. These bars carry the wires 12 and move the wires out of the annular grooves 13 to permit the springs 9 to restore the buttons 5 to elevated position. The hub of the handle 29 indicated at 32 is splined upon the shaft 30 so that it may slide toward or from the frame 23. When thrust toward said frame and rocked rearwardly it resets the keys as hereinbefore described while if rocked forwardly when in this position a cam 46 upon shaft 30 acts against a roll 47 upon the frame 23 to thrust the frame toward the type bars to bring about the printing action. If the handle be slipped outwardly or away from the frame 23, the arm 31 is moved out of alignment with plunger 33 and then the frame 23 may be swung rearwardly to carry the platen away from the type bars and to a position where a fresh sheet of paper may be inserted. Downward movement of the bar 37 under the action of spring 36 is limited by the stops 37a of brackets 37b.

The lever 48 (see Fig. 1) is like the corresponding levers commonly employed upon typewriters for imparting a step by step movement to the platen of such typewriters. This common mech-

anism serves through the usual connections to impart a like step by step movement to the platen 22 and I utilize this old mechanism to actuate the ribbon feed illustrated in Fig. 2. The ribbon 5 27 is shown engaged at one end with a roll 49 carrying a ratchet wheel 50 that is engaged by a pawl 51. When the handle 48 is moved to thrust the actuating bar 52 of the platen forwardly, it also moves the pawl 51 to impart a 10 limited movement to the roll 49 and consequently to the ribbon 27.

While I may, if desired, print the units of the scrambled message upon paper in a continuous line and without any spacing, it is advantageous 15 from the standpoint of facilitating the scanning of the message to provide means whereby some of the type bars may be held in such elevated position that they will print neither a dot nor a dash to the end that blank spaces will appear 20 in the completed line of units. The mechanism for effecting this is illustrated in Figs. 1, 6, 7 and 8. A rock shaft 53 carries an operating handle 54 and when thrust downwardly as in Fig. 6, moves tappet arms 55 upwardly. These arms 25 thrust against blocks 56 guided by vertical rods 57. These blocks have slots 58 formed in them through which screws 59 pass. The inner ends of these screws engage in blocks 60 which carry opposed angle plates 61 and 62. By loosening 30 the screws 59 the blocks 60, with their angle plates, may be shifted bodily to the right or to the left, as the case may be, to the limit of the slots 58 and may then be bound in the position to which they are moved by the tightening of 35 the screws 59. Some of the type bars, for example, every fifth type bar, may be provided with an enlarged head 63 adapted to be engaged by the horizontal extension of the angle plate 62 while other of the type bars, for example, every 40 sixth type bar, may be provided with an enlarged head 64 (see Fig. 7) which faces in the opposite direction from the corresponding member of Fig. 6 and is adapted to be engaged by the horizontal portion of the angle plate 61. 45 Thus, if the handle 54 (Fig. 6) be elevated to lower the block 56 to such position that the notches 63 of every fifth type bar are brought into alignment with the horizontal portion of the angle plate 62 and at a time when the type 50 bars are in their lowered and normal positions and if the screws 59 are loosened to permit the angle bars to be shifted to the left to engage angle bar 62 in the notches 63, the type bars so engaged will be elevated against the tension 55 of their actuating springs when the handle 54 is again thrust downwardly. Under those circumstances, there would be a blank space between each group of four units in the printed line. By carrying out the foregoing operation 60 but with the angle plates shifted to the right, as in Fig. 7, then every sixth type bar will be elevated to non-printing position and the units of the garbled message will appear upon the printed line in groups of five with spaces between them. 65 This not only facilitates the scanning of the message but as will be presently set forth, increases the garbling of the message because it is possible through the use of the panels P, P' and P² to press the keys in groups of five to print 70 five units but to have these units appear in groups of four. This does not mean, however, that one of the units has been lost but only that the fifth unit has been carried over into the next succeeding group of four units in the printed line. 75 These panels P, P' and P² constitute an exceed-

ingly important part of the present invention. By referring to Fig. 4 it will be seen that the mechanism hereinbefore described is contained within a casing comprising a cover section C and a base section B, the cover section being adapted to merely lift off after the manner of a typewriter cover. The mechanism rests upon a plate C' which is hinged at H to the base B and this plate C' carries a handle C² by which the plate with the mechanism mounted thereon may swing 10 upwardly to expose the compartment constituted by the base section B and this base section is utilized for the reception of the panels and their associated parts. Each panel comprises a pair of plates 64 and 65 having a row of metallic 15 contact studs 66 along their opposite edges. These panels are adapted to be fitted upon studs 67 upstanding from a sheet of insulating material 68 and held firmly in place by thumb screws 69 upon said studs. The contact studs 66 engage 20 the rows of contact strips 70, 71 and 72. The panel P which is the intake panel may be termed a substitution and spacer panel. The center panel P' is a transposition panel while the panel P² also functions as a substitution and spacer 25 panel. These panels P² have the rows of contacts upon their opposite edges connected by wires 73 which extend across the panels and make contact upon the opposite sides thereof in any desired order. However, these wires may 30 connect these opposed contacts in groups of four or in groups of five and various other arrangements may be resorted to. The center or transposition panel P' has its connecting wires 74 crisscrossed as indicated in Fig. 15 so that an 35 electrical impulse delivered through the contact 71 to one side of this panel at a given point may be delivered to one of the contacts 72 at a point materially out of line with the delivering contact 71. The combined effect of thus transposing 40 units of the characters through the transposition panel and of substituting some of the elements of one character for an element of the next succeeding character as, for example, where we 45 depress the keys in groups of five and print in groups of four, or vice versa is to so heterogeneously mix the fractional units of characters as to constitute a scrambled whole in which 50 there is no determined continuity and no definite beginning or ending of individual characters. The net result of this is to produce a secret message which cannot be decoded by any human being no matter how skilled he may be in such work.

When using this machine to decode a garbled 55 message at a receiving station, the operator takes the printed sheet containing such garbled message or a double thereof and with that sheet as a guide taps upon the keys of the key board 60 designations corresponding to the units of the garbled message and by the use of properly or reversely wired panels he can bring about such reversal of the steps that took place in the formation of the message as to restore the message 65 to straight text or intelligible form.

The garbled message may be transferred from 70 sending to receiving station by messenger, mail, radio, telegraph, or any other practicable way. Thus there is no necessity for any synchronization at the sending station and rate of operation of the machine used at the receiving station.

Referring now to Figs 1 and 16, 76 designates an L-shaped shield adapted to be swung into 75 such position as to overlie the right hand row

of keys and to prevent the operation of this right hand row when the transmission of the units of the garbled message is in groups of four. When this shield is used the three lower rows of keys are used. In other words, we use either twelve rows of five keys or a total of sixty keys or fifteen rows of four keys, again a total of sixty keys.

As has been previously stated, each letter consists of five units or at least it does so in the particular embodiment of the invention chosen for purposes of illustration. It would, of course, be possible to assign more or less units to a letter. However, referring to the particular embodiment shown in the drawings and more particularly to the diagrammatic Fig. 12, it will be seen that, when the proper keys in a row have been punched on panel P, which is the input or substitution panel, a character has been formed. However, since, as indicated at p, in Fig. 12, the connecting wires crossing this panel may be crossed to get a different relation of contacts at the far side of the panel fed in at the input edge of the panel we will have at the output edge of panel P another arrangement of five units making up a character but a different character from that which has been fed in at the input side. In other words, this panel P is as previously stated, a true substitution panel, substituting one character for another. The effect of the panel P is that when a, for example, is played on the first line of keys it is converted to something else in the first five group unit and to something else again in each of the succeeding eleven five group units of said panel according to where it falls in the key board. The importance of this is that if a letter such as a were played through the transposition panel P' without the intervention of the substitution panel P, it would always produce the same pattern in the equivalent for any given line of the key board; that is, a on the first, fifth and tenth key lines of the key board would produce identical and consequently possibly discernible values in the ultimate pattern but with the substitution panel P interposed, the possibility of the code being broken from the aforesaid cause is positively eliminated. The third panel P² has also a form of substitution and serves to further protect the secrecy of the formed message by substituting one character for another and this in a constantly changing and non-repeating fashion and by this scrambling the component units of said letters through the heterogeneous crisscrossing of the wires of panel P' I provide an unbreakable code forming method and apparatus.

Referring now to Fig. 17, the panels P⁵, P⁶ correspond to the input panel P in Fig. 12. The buttons 5X, 5Z represent two of the sixty buttons on the key board. In using the distributor illustrated in Fig. 17, I prefer to eliminate the spacing in fours and use the hereinbefore described spacing in fives. This is easily accomplished by merely placing the proper five spacer panel in position and lifting the proper spacer keys as described. A source of current, such as a battery L, is grounded at one side to the frame of the machine and its other terminal is connected to a rotative post J which carries a swinging contact arm G. Any suitable means may be employed for moving this arm G to bring it into engagement with the contacts F, F¹, F², F³, etc., said contacts being spaced circumferentially upon a disk N. One form of operating mechanism comprises a plunger H, the inner end of which constitutes a pawl adapted to

engage a suitable ratchet upon the post J. The contacts F, F¹, F² are connected by wires O to the terminals Q of a block R. Panels P⁷, P⁸ are arranged to deliver the current from the contacts F¹, F², etc. to wires D, D' through the binding posts D, D' and in such irregular fashion as may be determined by the winding of said panels P⁷, P⁸. I would prefer to superimpose the last named panels but for the sake of preserving the clarity of the drawings, I have shown them disposed side by side. Furthermore, I may use more than two panels if desired. The wires D, D' are attached to spring contacts D², D³ adapted to be depressed in unison by either of the buttons 5X, 5Z, these buttons being insulated as indicated at z. When depressed, the contacts D², D³ engage the contacts E, E' and it would depend upon the position of the arm G of the distributor as to which of the circuits D, D' would be energized. That is to say, the wiring from contacts F, F', etc. in the distributor through the distributor panels P⁷, P⁸ would determine which of either D² or D³ was alive and in condition to route current through the panel P⁵ or P⁶.

The contacts E, E' are connected by the conductors b, b' to the intake sides of the panels P⁵, P⁶, the other sides of said panels being connected as hereinbefore described through contacts 11a to either the transposition panel or panels or to the solenoids or otherwise.

It will be observed that whereas the structure hereinbefore described with respect to the set-up of Fig. 12, for example, permits a complete substitution of letters through the substitution panel P, the distributor of Fig. 17 when added to the system provides for a perpetual shifting of the sequence of these substitutions, which gives us a system which not only cannot show any repeats in the same message, but even in a plurality of messages and even where the first twenty-four letters were known, the balance of the message would still be unknown because the distributor introduces unknown sequence variations into the shifting flow of the substitution panels as well as into the sequence of transposition in the transposition panel.

M indicates a fragment of a cover over the distributor, said covering having a sight opening m therein through which a spot K on the arm G is visible. This furnishes a starting point common to all new messages and agreed on between sender and receiver.

It will, of course, be understood that what it is desired to protect is not only the particular mechanical structure that has been chosen for purposes of illustration, but any substantial equivalent thereof. Consequently, it is to be understood that the invention includes within its purview whatever changes fairly come within either the terms or the spirit of the appended claims.

Having described my invention, what I claim is:

1. Apparatus of the character described comprising a plurality of groups of keys, printing bars controlled by said keys, at least two characters carried by each of said bars, means for impressing said characters upon a message carrier at a printing position, one of the group of characters of all of the keys normally lying in printing position, and means for shifting said bars under control of said keys to move the latter characters out of printing position and to bring the other characters of the bars into printing position.

2. Apparatus of the character described comprising a plurality of circuit closing keys, a plu-

- rality of type bars, electrical controlling means for the type bars, electric circuits in which said keys and said controlling means are included, there being one of said circuits for each of said type bars, and a transposition panel having criss-cross connections incorporated therein which connections constitute a part of the respective circuits for the purposes set forth.
3. An apparatus of the character described comprising a plurality of circuit closing keys, a plurality of message forming bars corresponding in number to said keys, electrically actuated controlling elements for said bars, separate electric circuits in which said elements and the keys are included, and a plurality of interchangeable panels carrying connections constituting parts of the several circuits and disposed in said circuits, at least one of said panels being provided with crisscross connections to bring about scrambling of the resultant message produced by the message forming bars.
4. An apparatus of the character described comprising a plurality of circuit closing keys, a plurality of message forming bars corresponding in number to said keys, electrically actuated controlling elements for said bars, separate electric circuits in which said elements and the keys are included, and a plurality of interchangeable panels carrying connections constituting parts of the several circuits and disposed in said circuits, at least one of said panels being provided with crisscross connections to bring about scrambling of the resultant message and at least one other of said panels having its connections thereacross arranged in spaced groups.
5. A machine of the character described comprising a multiplicity of circuit closing keys, electric circuits in which said keys are included, a plurality of character carrying type bars, magnets for controlling the movement of said type bars, said magnets being likewise included in said circuits and there being one of said circuits for each of said magnets, and a panel comprising a row of contact members along each of its edges and crisscross connections between the contact members which are disposed in said circuits when said panel is in place.
6. A structure as recited in claim 3 in combination with a printing mechanism associated with the character type bars, said printing mechanism comprising a platen, and means for forcibly moving said platen toward the type bars.
7. A structure as recited in claim 3 in combination with a platen, a handle for actuating said platen and mechanism controlled by said handle for resetting the type bar to normal position.
8. A structure as recited in claim 3 in combination with a printing mechanism comprising a swinging frame mechanism comprising a manually operable handle for swinging said frame to move the platen forcibly toward the type bars, and a ribbon disposed between the type bars and the platen.
9. A structure as recited in claim 3 in combination with a printing mechanism comprising a swinging frame mechanism comprising a manually operable handle for swinging said frame to move the platen forcibly toward the type bars, and a ribbon disposed between the type bars and the platen, and mechanism actuated by said handle for restoring the type bar and the keys to normal position.
10. Apparatus of the character described comprising a key board, a printing system and a plurality of panels interposed between the key board and printing system and constituting parts of electric circuits through which the movements of the character on the key board is imparted to the elements of the printing system, the wires of one of said panels being so disposed as to convert characters delivered to the input edge of said panel to a different character at the output edge of said panel and the wires of another of said panels being so disposed as to transpose the individual units which form such characters.
11. Apparatus of the character described, comprising a message forming mechanism including a plurality of keys controlling the message forming elements of said mechanism, an electric circuit controlled by each of said keys, a panel cross-wired to form an input letter substitution panel, the cross connections of which are included in said circuits when said panel is in place, a distributor interposed in the said circuits, and means for causing said distributor to repeatedly shift the sequence of the substitutions effected by said panel.
12. An apparatus as recited in claim 11, wherein the distributor comprises a movable contact arm, means for causing said arm to travel, a plurality of contacts with which the arm engages in its travel, a pair of panels, means for connecting some of said contacts to one of said panels and for connecting other of said contacts to the other of said panels, and circuits controlled by said keys and constituting connections between the last named panels and the letter substitution panel whereby determination as to which of the circuits of the substitution panels will be energized by the closing of a key is controlled by the position of the contact arm of the distributor.

JOSEPH B. WALKER.
